SNUBBED TRUCK

Walter L. Schlegel, Jr., Chicago, Ill., assignor to American Steel Foundries, Chicago, Ill., a corporation of Illinois

Application September 20, 1951, Serial No. 247,458

12 Claims. (Cl. 105—197)

This invention relates to railway car trucks and more particularly to a truck in which novel friction snubbing means are provided for damping vertical, lateral and out-of-square movements of a truck bolster relative to the supporting side frames.

Prior art trucks of this type have incorporated complicated snubbing devices in which a great number of parts have been required, resulting in expensive and complicated truck and snubbing parts. Some of these prior art devices have utilized one or more shoes associated with each column of the truck side frames, in combination with one or more shoe actuating springs associated with the shoe or shoes at each column. Other snubbed trucks have utilized a plurality of friction shoes associated with the side frame columns, in combination with one or more springs and actuating plates or wedges for transmitting thrust of the springs to the shoes.

Accordingly, a primary object of the present invention is to devise a novel snubbing device consisting of three parts, namely, two shoes and one actuating spring so arranged that the spring is effective to urge the shoes against the respective columns under substantially constant pressure during vertical oscillation of the bolster on its supporting springs.

Another object of the invention is to devise a snubbing device such as above described, wherein the side frame may be of standard construction and the bolster may be of very simple form without the necessity of providing complicated wedge surfaces or friction shoe housings therein.

Another object of the invention is to urge the friction shoes under substantially constant pressure against one of the top or bottom bolster walls to prevent shoe chatter resulting from relative vertical movement between the bolster and shoes under service conditions.

Another object of the invention is to prevent friction shoe chatter resulting from relative lateral movement between the bolster and shoes under service conditions.

The foregoing and other objects and advantages of the invention will become apparent from a consideration of the following specification and the accompanying drawings, wherein:

Figure 1 is a fragmentary side elevational view of a freight car truck embodying a preferred form of the invention;

Figure 2 is a top plan view of the snubbing device with the bolster and side frame columns shown in horizontal section, and

Figure 3 is a vertical sectional view on the line 3—3 of Figure 1.

Describing the invention in detail, the truck comprises a side frame having a compression member 2, a tension member 4 and spaced columns 6 defining a central bolster opening 8 and windows 10 adjacent the ends of the frame which are adapted for connection in the usual manner to associated wheel and axle assemblies (not shown).

A bolster generally designated 12 is supported within

2

the bolster opening 8 by springs diagrammatically indicated at 14 and supported by a spring seat 16 on the tension member 4 at the bottom of the bolster opening 8.

As will be readily understood by those skilled in the art, the bolster 12, as shown in Figure 3, extends transversely of the truck and projects at each end thereof into the bolster opening 8 of the related side frame for support by the spring 14 thereof. In the drawings, only one end of the bolster and related side frame and snubbing means are illustrated inasmuch as the corresponding structure at the opposite end of the bolster is preferably identical.

At each side thereof, the bolster is provided with inboard and outboard gibs 18 and 20 loosely confining the columns 6 to accommodate vertical, lateral and out-of-square movements of the bolster 12 as are desirable under various conditions of railway service. Between the gibs 18 and 20 at one side of the bolster, the latter is formed with a transverse wall member 22 which is preferably diagonal with respect to the vertical, as best seen in Figure 3, for a purpose hereinafter described.

The inboard side of the wall member 22 is frictionally engaged with a friction shoe 25 along complementary preferably flat wedge faces of the shoe and wall sloping downwardly and outboardly, as shown in Figure 3. One end of the shoe 25 is engaged with a friction surface 27 on the related column 6, said friction surface preferably being provided on the wear plate 28, attached in any convenient manner to the column. The opposite end of the shoe 25 is formed with a wedge surface 30 which, as seen in the top plan view of Figure 2, is disposed diagonally with respect to the longitudinal vertical center plane X—X of the bolster 12. The wedge surface 30 of the shoe 25 is engaged with a complementary wedge surface 32 at the corresponding end of a friction shoe member 34, the opposite end of which is engaged with a friction surface 27 on a wear plate 28 of the related column 26.

Actuating means are provided for the shoe 25 and shoe member 34 in the form of a compression coil spring diagrammatically indicated at 36. The inboard end of said spring is compressed against a bolster spring seat wall or lug 38, and the outboard end of the spring 36 is compressed against the inboard side of the friction shoe member 34. It may be noted, as best seen in Figure 3, that the compressional axis of the spring 36 slopes downwardly and outboardly toward the wall member 22, which is arranged in converging relationship with respect to the wall 38, whereby both the shoe 25 and shoe member 34 are maintained against vertical chatter resulting from relative vertical movement of the bolster 12. Thus it will be understood that the diagonal sloping arrangement of the spring 36 causes a vertical force component on the shoe member 34 holding it tightly against the bottom wall of the bolster 12, said bottom wall extending longitudinally of the bolster 12 as will be understood by those skilled in the art. The spring 36 is also effective to urge the shoe member 34 outboardly into wedge engagement at 30, 32 with the friction shoe 25 whereby the shoe and shoe member are urged, respectively, against the related column surfaces 27.

It may also be noted, as best seen in Figure 2, that the compressional axis of the spring 36 is defined by a vertical plane substantially parallel to the plane X—X and to the planes of the friction surfaces 27 whereby a force component of the spring 36 is afforded to urge the shoe 25 outboardly against the bolster wall member 22 which preferably slopes downwardly and outboardly thereby holding the shoe 25 against the bottom bolster wall preventing vertical chatter of the shoe 25.

Thus it will be understood that in the novel arrangement above described, the shoe and shoe member are

positively interlocked with the bolster against substantial relative movement thereof, whereby vertical and lateral oscillations of the bolster and the springs 14 are snubbed by frictional engagement with the column surfaces 27; and out-of-square bolster movements relative to the side frame are frictionally resisted by engagement of the shoe and shoe member with the bottom bolster wall.

An important feature of the invention resides in the arrangement of parts which reduces the components of the snubbing device to a minimum, inasmuch as one spring 36 is sufficient to actuate both the shoe and shoe member under substantially constant pressure against the side frame columns and against the bottom bolster wall. Although it will be understood that, if desired, another spring 36 may be interposed between the engaged faces of the shoe 25 and wall member 22 by positioning the wall member 22 at approximately the outboard end of the bolster 12.

I claim:

1. In a railway car truck, a side frame having spaced columns with substantially parallel, transverse friction surfaces, a bolster spring-supported between said columns, said bolster having a wall member extending transversely thereof toward one of the columns, a friction shoe engaging said column and wall member, a friction shoe member engaging the other column, said bolster having a bottom wall supporting said shoe member, spring means compressed between the bolster and the shoe member for urging the latter outboardly, said spring means having its compressional axis extending downwardly and outboardly to hold said shoe member tightly against said bottom wall, and interengaged wedge surfaces on the inner ends of said shoe and shoe member arranged diagonally with respect to said column surfaces, whereby said spring urges said shoe against said wall member and urges said shoe and shoe member against the respective columns, and means on the shoe and wall member for holding the shoe against the bolster wall.

2. A railway car truck according to claim 1, wherein the last mentioned means are characterized by interengaged surfaces on the wall member and shoe sloping downwardly and outboardly lengthwise of the bolster.

3. In a railway car truck, a side frame comprising spaced columns having transverse friction surfaces disposed in approximately parallel planes, a bolster spring-supported between said columns, friction shoes housed within the bolster in frictional engagement with respective surfaces, the longitudinal vertical center plane of the bolster being approximately parallel to the first mentioned planes, said bolster having a transverse wall and a longitudinal wall, said friction shoes having complementary interengaged wedge surfaces arranged diagonally with respect to said planes, and sloping spring means engaged with the bolster and one of the shoes for urging said one shoe against the longitudinal wall and for urging said wedge surfaces into engagement and thereby urging said friction shoes against the respective column surfaces, and means on the transverse wall and other shoe for holding the latter against the longitudinal wall.

4. A railway car truck, according to claim 3, wherein the wedge surfaces are approximately vertical.

5. A railway car truck according to claim 3, wherein the last mentioned means are characterized by interengaged surfaces on the transverse wall and said other shoe sloping lengthwise of the bolster.

6. A railway car truck, according to claim 3, wherein the spring means are characterized by a compression spring compressed between the bolster and one of the

shoes on an axis falling within a vertical plane parallel to the longitudinal, vertical center plane of the bolster.

7. In a railway car truck, a frame member having spaced friction surfaces, a bolster member movable with respect to said surfaces, and a friction device carried by the bolster member comprising a shoe and a shoe member engaged with respective surfaces, said shoe and shoe member having interengaged wedge faces diagonal with respect to said surfaces, and sloping spring means compressed between the bolster and the shoe member for urging said wedge faces into engagement and for urging said shoe member into contact with a substantially horizontal surface of the bolster member, and means on the shoe and on the bolster member for holding the shoe against said substantially horizontal surface.

8. A railway car truck, according to claim 7, wherein the wedge faces are vertical, and the last mentioned means are characterized by interengaged surfaces of the shoe and bolster member sloping longitudinally of the bolster member.

9. In a railway car truck, a side frame, a bolster spring-supported thereby, and friction means for damping oscillations of the bolster comprising spaced friction surfaces carried by the frame, friction shoes engaged with respective surfaces and having directly interengaged wedge surfaces diagonal with respect to said friction surfaces, sloping spring means for urging the wedge surfaces into engagement with each other whereby the shoes are engaged with respective friction surfaces, said spring means being operative to limit relative vertical movement of one of the shoes with respect to the bolster, and independent means associated with the other shoe for limiting relative vertical movement of the bolster with respect thereto.

10. A railway car truck having spaced columns, a bolster therebetween, and friction means for controlling bolster oscillations comprising friction shoes in direct wedge engagement with each other and in frictional engagement with respective columns, a spring compressed between the bolster and one of the shoes on a sloping compressional axis to prevent vertical chatter of said one shoe relative to the bolster, and means on the bolster for preventing vertical chatter of the other shoe relative to the bolster.

11. A railway car truck comprising a frame member with spaced columns, a bolster therebetween, friction shoes housed in the bolster, said shoes being in direct wedge engagement with each other and being frictionally engageable with respective columns, a sloping spring compressed between the bolster and one shoe for urging the latter against the bolster and for urging said shoe into said wedge engagement, and means on the bolster engageable with the other shoe for transmitting reaction of said spring to said bolster.

12. A railway car truck, according to claim 11, wherein said means comprise a surface on the bolster between its top and bottom walls and engaged with a complementary surface of the said other shoe.
